UNITED STATES PATENT OFFICE.

JOSEPH V. WECKBAUGH, OF NEW YORK, N. Y., ASSIGNOR TO AMERICAN CUPTOR CORPORATION, OF NEW YORK, N. Y., A CORPORATION OF DELAWARE.

DRINKING CUP AND METHOD OF MAKING THE SAME.

Application filed September 16, 1925. Serial No. 56,633.

The present invention relates to drinking cups of the type in which a blank in the form of a parallelogram is bent about a diagonal and has the two edges, which are thus brought together, united by being folded over and then held in place by a metal strip. A cup of this general type is shown in my earlier Patent No. 1,421,114, issued June 27th, 1922.

10 In that earlier patent I pointed out that it is desirable to use a metal strip perforated along its median line. I still utilize such a strip, but I find that the perforations can be made to serve an additional function 15 not pointed out in the earlier patent. If the metal is simply bent into V shape and then clamped about the folded edges of the paper a useful cup is formed but it will be found to be somewhat fragile, as the paper may pull out of the metal under the strain of the liquid contents. For this reason it is desirable to lock the metal in place, particularly if the metal used is soft enough 20 to be applied readily. I have now found that the use of a metal strip having relatively large perforations which are arranged quite close together, lends itself to a highly efficient method of locking the metal in place.

25 In the accompanying drawings I show my present invention applied to a cup of the same general type as illustrated in my said earlier patent. In these drawings Fig. 1 is a perspective of the cup; Fig. 2 is an enlarged detail of the seam; Fig. 3 is a section 30 on line 3—3 of Fig. 2; and Fig. 4 shows a modification, the view being similar to that shown in Fig. 3.

35 After the two edges of the blank 2 are brought together and folded over as shown 40 at 3, the metal binding strip 4, in which are perforations 5, is bent along its median line (that is through the center of the perforations 5) and compressed about the folded 45 edges. After this is done the portions of the metal which lie between the perforations will appear as bands running around the edge of the cup. Such bands are indicated at 6 in Fig. 2. I have found that the metal 50 strip can be securely locked in place if certain of these bands, together with the portions of the paper which they embrace, are distorted or pushed out of their general plane. In the illustrative example I have 55 shown a minor proportion of the bands dis-

torted as indicated at 7, and this has been found to be sufficient for a cup of good strength.

In Figs. 3 and 4 I show two ways in which the bands and the paper can be distorted. 60 In Fig. 3 the edge of the paper and the metal band are compressed so that they bulge out to form a T-shaped cross section. This may be done by holding the inner edges of the metal strip at both sides and then pressing 65 the free edge with a flat instrument. Mechanism for forming this seal mechanically is shown in my copending application Serial No. 55,596, filed September 10, 1925.

In Fig. 4 the bands 6' and the folded edges 70 3' are locked together by pushing the bands and paper over sideways. This may be done in any desired manner, or can be done mechanically by using apparatus similar to that shown in my Patent No. 1,574,324, dated 75 February 23, 1926, which was co-pending with the present case.

In either case it may be noted that the paper is distorted in a way that must involve some internal strains, which, however, are 80 of insignificant magnitude and demand but little force. The metal on the other hand, which would be more difficult to distort in this way, is simply bent, for the perforations allow the intermediate bands some freedom 85 of movement. I am thus able to produce a cup with a firmly sealed edge which demands a minimum amount of force or power for its manufacture.

What I claim is:

1. In a paper drinking cup having two edges of a blank brought together and folded over, a seal comprising a metal strip with relatively large perforations along its median line folded about such median line and embracing said folded edges, certain of the portions of the metal lying between the perforations, together with the embraced paper, being distorted out of their plane to lock the metal in place.

2. A structure as defined in claim 1, in which the distorted portions of the metal and paper are formed to give a T-shaped cross section.

3. The method of sealing together the edges of a drinking cup or the like, which comprises the steps of folding over the two edges which are to be united, clamping about such folded edges a metal strip perforated along its median line and bent along the line

of such perforations, and sealing such strip in place by distorting certain of the portions of the metal which lie between the perforations together with the embraced paper.

5. 4. A method as defined in claim 3, in which the metal and the paper are distorted in such a manner as to form a T-shaped cross section.

5. A method as defined in claim 3, in which the distortion is effected by holding the inner edges of the metal on both sides while 10 pressing the portions to be distorted against a surface.

JOSEPH V. WECKBAUGH.
